UNITED STATES PATENT OFFICE.

GEORGE HENRY WHEARY, OF RACINE, WISCONSIN.

AUTOMATIC LOCKING MEANS FOR TRUNKS.

1,134,175.

Specification of Letters Patent.

Patented Apr. 6, 1915.

Application filed April 27, 1912. Serial No. 334,844.

To all whom it may concern:

Be it known that I, GEORGE H. WHEARY, a citizen of the United States, and resident of Racine, in the county of Racine and State of Wisconsin, have invented new and useful Improvements in Automatic Locking Means for Trunks, of which the following is a description, reference being had to the accompanying drawings, which are a part of this specification.

This invention relates to improvements in automatic locking means for trunks more particularly adapted for use in connection with trunks having a plurality of locking bolts.

In wardrobe and other like trunks which are divided medially, vertically to form a wardrobe section and a body section, the wardrobe section is usually provided with a top or upper end cover for convenience in removing garments from wardrobe sections. In trunks of this type a plurality of keyed locking devices is usually provided for locking the sections and the cover in closed position. The independent operation of these locking devices is not convenient and requires considerable time and is otherwise objectionable.

It is one of the objects of the present invention to overcome the before mentioned objectionable features and provide a trunk with a plurality of locks which may be unlocked by a keyed engagement with one of the locks.

A further object of the invention is to provide an automatic locking means adapted to lock trunk sections and a trunk cover at a plurality of points, one of the locking means being constructed and arranged to automatically unlock the parts which are locked thereby when the other locked parts are unlocked and opened.

A further object of the invention is to provide a locking member which is normally in unlocked position and which is moved to a locking position when another portion of the trunk controlled by an unengaged lock is moved to closed position.

A further object of the invention is to provide an automatic locking means for

trunks which is of simple construction, is strong and durable and which is well adapted for the purpose described.

With the above and other objects in view, the invention consists of the improved automatic locking means for trunks and its parts and combinations as set forth in the claims and all equivalents thereof.

In the accompanying drawing in which the same reference characters indicate the same parts in all of the views: Figure 1 is a front view of a trunk provided with the improved automatic locking means; Fig. 2 is a rear view of the trunk with the wardrobe section of the trunk shown in section to show the locking mechanism within the said section, the top cover of the said wardrobe section indicated by dotted lines as in open position; Fig. 3 is a vertical sectional detail view of the upper portion of the trunk; Fig. 4 is a vertical sectional detail view of the locking means shown in locking position, and Fig. 5 is a similar view with the locking means shown in open position.

Referring to the drawing the numeral 8 indicates a trunk body which is divided vertically to form a body portion 9 and a wardrobe section 10, the wardrobe section being open at its upper end and covered by a top cover 11 which is hinged to the forward edge of the body portion. The top cover is locked to the wardrobe section by a hasp lock 12 which is controlled by a key 13 in the ordinary manner while the wardrobe section is locked to the body portion by an automatic hasp lock 14 controlled by the movement of the top cover 11.

The hasp lock 14 comprises the hinged hasp member 15 attached to the body portion of the trunk and the bolt casing 16 attached to the wardrobe section thereof. The hasp member 15 is of ordinary construction and is provided with the usual keyed projection 17 which is adapted to extend through the opening 18 of the bolt plate 16 and into the trunk and to be engaged by the slidable bolt 19 forming part of the bolt member 15. The rectangular bolt 19 is slidably mounted within the bolt casing 16 and is provided with a stem 20 to

which passes through a medially positioned guide partition 21 forming part of the bolt casing. The outer end of the stem of the bolt extends slidably through the yoked end 22 of an actuating rod 23 slidably mounted on the inner side of one of the walls of the wardrobe section, and is held in engagement with the rod yoke by a transverse pin 20. The yoke portion 22 is of a length to permit the bolt stem to reciprocate therein a sufficient distance to permit the bolt to be pushed to unlocking position by the hasp member when the hasp member is pressed into locking engagement with the bolt. A heavy unlocking coil spring 25 surrounding the bolt stem and interposed between the yoked end 23 and the medial partition 21 serves to normally hold the bolt in unlocked position. A locking coiled spring 26 also surrounds the bolt stem and interposed between the medial partition and the rectangular bolt is of less strength than the first mentioned spring and is adapted to yieldingly hold the bolt in hasp engaging position when the unlocking spring is compressed by a downward pressure exerted on the rod. The locking end of the rectangular bolt is beveled as indicated by the numeral 19' and the inner end 17' of the hasp projection 17 is likewise beveled to provide for the automatic locking engagement of the two parts when the hasp member is pushed into locking position.

The actuating rod 23 extends through guide brackets 24 to a position to be engaged by an angular plate 27 mounted on and carried by the top cover 11 so that when the top cover is in closed position the actuating rod 23 will be pushed downwardly to such an extent as to compress the unlocking spring and permit the locking spring to move the bolt to locking position. The hasp members of each lock are provided with flat springs 28 of ordinary construction which swing the hasp members to open position when released by the lock bolts.

While the cover is shown as preferably provided with a rod-engaging plate, it is to be understood that this is not absolutely necessary as the upper end of the actuating rod may be engaged by any portion of the cover.

In use the trunk portions are closed in the usual manner and if it is desired to lock the parts together it is only necessary to press the hasp members of the respective locks to locking position and the parts will be automatically locked. Now, if it is desired to unlock the trunk, the top cover lock is unlocked with a key and upon raising the top cover the actuating rod will be disengaged and the unlocking spring will slide the bolt upwardly to unlocking position and the spring actuated hasp member will swing to

open position. While the cover is shown as controlling but one lock, it is to be understood that the invention contemplates a plurality of locks controlled by the cover in the same manner.

From the foregoing description it will be seen that the automatic locking means for trunks having a plurality of hinged together elements is of very simple construction and is well adapted for the purpose desired. 75

What I claim as my invention is:

1. The combination of a trunk having a plurality of connected-together elements, of an automatic locking means therefor, consisting of a locking member for two of the elements controlled by the movement of a third element. 80

2. The combination of a trunk having a plurality of hinged-together elements, of an automatic locking means therefor, comprising a manually actuated locking member locking two of the elements together, and an automatic locking member locking a third element to one of the locked-together elements, the second mentioned locking member being unlocked by the movement of one of the first mentioned locked-together elements toward its open position. 90

3. An automatic locking means for a trunk having a plurality of hinged-together elements, comprising a hasp member, a bolt member positioned to engage the hasp member, spring means for yieldingly holding the bolt member in unlocked position, and other means for yieldingly holding the bolt in locking position when the bolt member is relieved of the pressure of the first mentioned holding means. 95

4. An automatic locking means for a trunk having hinged-together elements, comprising a hasp member, a bolt member positioned to engage the hasp member, an actuating member engaging the bolt, a means for imparting a tendency to the bolt to move to a locking position, and a yielding means of stronger value for counteracting said tendency. 105

5. An automatic locking means, comprising a hasp member, a bolt member positioned to engage the hasp member, an actuating member having a slidable connection with the bolt, a coiled spring engaging the actuating member and exerting a tendency to move the actuating member in a direction away from the bolt, and a means of less tendency for moving the bolt to a locking position when the coiled spring is compressed. 115

6. An automatic locking means, comprising a hasp member, a lock casing, a bolt slidably mounted within the casing and provided with a stem and positioned to engage the hasp member, the casing being provided 120

with a guide shoulder through which the stem projects, an actuating rod slidably engaging the bolt stem, a coiled spring surrounding the bolt stem and interposed between the bolt and the guide shoulder, and another coiled spring surrounding the bolt stem and interposed between the guide shoulder and the actuating rod, said last men-

tioned spring being of greater strength than the first mentioned spring. 10

In testimony whereof, I affix my signature, in presence of two witnesses.

GEOERGE HENRY WHEARY.

Witnesses:

ANNA M. NELSON,
GEORGE BENNISH.
